UNITED STATES PATENT OFFICE.

HERMANN MERKEL, OF ST. LOUIS, MISSOURI.

DESIGN FOR A HYDROCARBON-BURNER.

SPECIFICATION forming part of Design No. 32,091, dated January 9, 1900.

Application filed November 22, 1899. Serial No. 737,955. Term of patent 7 years.

To all whom it may concern:

Be it known that I, HERMANN MERKEL, a citizen of the United States, residing in the city of St. Louis, State of Missouri, have invented and produced a new and original Design for a Hydrocarbon-Burner, of which the following is a specification.

Figure I is a side elevation of a hydrocarbon-burner embodying my new design. Fig. II is a plan.

As shown in the drawings, the leading or essential feature of my new design for a hydrocarbon-burner consists of the cylindrical portion 1, having the rectangular recesses 2 in its outer face; the vertical ribs 3 between the recesses 2; the vertical opening 4, extending through the center of the cylinder 1 and forming the mixing-chamber, the upper end of said opening 4 being enlarged to form the shoulders 5 and there being gas-openings 6 and 7 formed through the wall and connecting the mixing-chamber 5 with the recesses 2,

said openings 6 extending from the upper end of the cylinder to near the lower end of the recesses and said openings 7 being formed at 25 the lower ends of recesses; the shoulder 8 at the lower end of the cylinder 1; the substantially cylindrical portion 9, extending downwardly from the shoulder 8; the cylindrical portion 10, extending horizontally from the 30 lower end of the portion 9; the cylindrical arm 11, extending downwardly from the portion 10; the cylindrical portion 12, extending horizontally from the lower end of the portion 11, and the valve-easing 13 in a vertical position upon one end of the portion 12 in vertical alinement with the opening 4. 35

I claim—

The design for a hydrocarbon-burner, substantially as herein shown and described.

HERMANN MERKEL.
